WILLIAM ILE, OF NEW YORK, N. Y.

ATTACHMENT-PLUG.

1,313,089.

Specification of Letters Patent. Patented Aug. 12, 1919.

Application filed October 11, 1918. Serial No. 257,684.

To all whom it may concern:

Be it known that I, WILLIAM ILE, a subject of the King of Great Britain, residing in the city, county, and State of New York, have invented new and useful Improvements in Attachment-Plugs, of which the following is a specification.

This invention relates to separable electric attachment plugs, and it is the object of the invention to provide a plug of this character in which one member carries binding terminals for electric current conductors having extended terminal contact fingers which are adapted to be inserted into openings in another plug member to contact with contact terminal fingers carried by said latter member in said openings in electrical communication with contacts carried by said member adapted to coöperate with the contacts of a socket, and the contact terminal fingers of the two members being arranged to lock the plug members together and to be released by a predetermined force, and to provide a plug of this character in which the number of parts has been reduced and the assembling of the same has been simplified to produce a plug which is cheap to manufacture and novel in construction.

It is a further object of the invention to improve and simplify the construction of the plug member carrying the contacts to coöperate with a socket, whereby as such contacts are mounted upon or applied to the plug member they will operate to place and hold contact terminal fingers carried by said plug member in contact therewith and firmly and rigidly clamp said fingers to the plug member without the use of screws or the like.

In the drawing accompanying and forming a part of this specification, Figure 1 is a disassembled longitudinal sectional view of an electric attachment plug showing an embodiment of my invention and taken substantially on the line 1—1 of Fig. 2 looking in the direction of the arrows.

Fig. 2 is a side elevational view of the plug.

Fig. 3 is a plan view of the lower section 50 of the plug shown in Fig. 1.

Fig. 4 is a view looking at the top of the middle section of the plug shown in Fig. 1.

Fig. 5 is a view looking at the bottom of the middle section of the plug shown in Fig. 1.

Figs. 6 and 7 are front elevations of terminal contact fingers carried by one of the plug members; and

Fig. 8 is a side elevational view, partly in section, showing a modification of means to connect component parts of the plug.

Similar characters of reference designate like parts throughout the different views of the drawing.

As stated it is the object of the invention to provide a separable plug, and in the embodiment of the invention shown in Fig. 1 one member of the plug comprises a block of insulating material 7 having a circular recessed portion 8 in one end and an opening 9 axially therethrough for the passage of electric current conductor wires. Circuit terminal contacts 10, 11 carrying binding screws 12, 13 are carried within the recessed portion 8 and secured therein by screws 14, although the terminal contacts may be embedded or molded directly in the material of the member 7. These terminal contacts have terminal contact fingers 15, 16 extending therefrom in a direction parallel with the axis 80 of said member, and each finger has a laterally projecting nib 17, 18 stamped from the material of the fingers for a purpose to be hereinafter described.

The other member of the plug consists of a block of insulating material 19 externally threaded with perforations or openings 20, 21 extending longitudinally therethrough and preferably of rectangular shape in cross section. A portion of the lateral wall of the opening 21 is cut away to form a recess, as shown at 22, and the end of the block is formed with a recess 23 extending laterally and inwardly from the end of the opening 20.

A terminal contact finger 24 is carried by the member 19 to engage in the opening 21. This finger has a part bent upon itself to engage over the recessed wall of the opening with a part to lie contiguous to the outer surface of the plug member 19, and being formed with threaded sections 25 complementary to the threads of said member for a purpose to be hereinafter described. A portion of the finger in the opening is arranged to lie contiguous to one wall of the opening and has the end portion bent reversely upon itself, as shown at 26, to form a yielding portion to extend toward but spaced from the opposite wall of the opening. This portion

- 26 of the finger has a longitudinal flute 27 extending from the bend to adjacent the extremity with a perforation 28 at the end of the flute. (Fig. 7.)
- 5 A terminal contact finger 29 engages in the opening 20 and is so constructed and arranged that a portion thereof will engage with one wall of the opening and the end of the finger within the opening bent upon itself to form a yieldable portion 30 to extend toward but spaced from the opposite wall of the opening. This portion 30 is provided with a longitudinal flute 31 and a perforation 32 at the end of the flute (Fig. 6) similar to the yieldable portion of the finger 24. The finger extends transversely of the opening with a part to engage over the shoulder formed by the recess 23 and into the recess, and then bent to project from and beyond the block substantially coaxially therewith as at 33 and the extremity bent upon itself, said bent portion being of less width than the remaining portion of the finger and thereby forming shoulders at opposite sides of the finger at the juncture of the bent over portion with the finger, as clearly shown in Fig. 6. It will be noted that neither of the fingers 24, 29 are secured to the block 19, as by screws or the like.
- 30 The block or member 19 carries contacts to coöperate with the contacts of a socket. These contacts are in the form of a cap consisting of a threaded metallic sleeve 36 to be screwed onto and encircle the threaded periphery of the block 19. One end of the sleeve is embedded or molded in a band or annular member 37 of insulating material with the inner surface of the band of concave form. The sleeve carries at said end a metallic disk or eyelet 38 having an opening 39 centrally thereof and coaxially of the sleeve, as by embedding or molding a portion of the disk in the insulator member 37. The threads on the sleeve are complementary to and adapted to coöperate with the threaded shell of a socket, and the disk 38 to coöperate with the end contact of a socket.
- 50 As the sleeve 36 is threaded onto the block 19 the bent extremity of the projection 33 of the finger 29 will engage with the concaved or beveled wall of the annular insulator member 37 and be directed thereby into the central opening of the disk 38, and as said disk engages with the shoulders formed at opposite sides of the reduced extremity of the finger 29 it will force and clamp the bent portion of the finger against the bottom of the recess 23 and thereby forcibly press the portion of the finger in the opening 20 against the wall of the opening. As the sleeve is seated on the block it will clamp the finger 29 rigidly to the block 19 with the extremity of the projection 33 held in positive contact with the wall of the disk

perforation 39. The screw threads of the sleeve will also coöperate with the threaded section of the finger 24 to clamp said finger rigidly to the block and hold the sleeve in positive contact with said finger.

In the operation of assembling the plug in use the plug member 19 is screwed into a socket with the plug member 7 disassembled therefrom. To connect the plug sections or members the terminal contact fingers 15, 16 of the member 7 are inserted into the openings in the member 19, these fingers being so arranged that they will engage in the spaces between the wall of the openings and the yieldable portions 26, 30 of the fingers 24, 29, such spaces being slightly less in width than the thickness of the fingers 15, 16, and the yieldable portions of the fingers 24, 29 being so tensioned that the fingers 15, 16 may be pushed into the openings 20, 21 without jarring or exerting too great a strain upon a lamp or the like to which the socket is connected. As the fingers 15, 16 are inserted the finger nibs 17, 18 will pass along the fluted portions 27, 31 of the fingers 24, 29, and as the plug members abut such nibs will be in position to engage in the perforations 28, 32 at the ends of the fluted portions, thereby locking the plug members together. It will be obvious that by exerting a pull on the plug member 7 with a force which is predetermined in accordance with the tension of the yieldable portions of the fingers 24, 29 that the plug members 7, 19 will be released.

The plug member 19 may have an annular flange 41 with the periphery of the flange knurled to facilitate the screwing of the plug member 19 into and out of a socket. The plug member 7 may also be provided with an annular knurled portion 42 to provide a finger grip to facilitate the releasing of the plug members.

The construction of the plug shown in Fig. 8 is similar to the plug shown in Figs. 1 to 7 with the exception that the extremity of the finger projection 33 is threaded, as shown at 43, to coöperate with internal screw threads formed on the wall of the disk perforation 39, and thereby as the sleeve is threaded onto the plug member 19 this threaded connection between the extremity of the finger projection 33 and the disk contact will operate to lock the sleeve onto the plug member.

Having thus described my invention, I claim:

1. In an electric attachment plug, a base of insulating material having openings therethrough, terminal contact members to engage in said openings; and means mounted upon the base constituting an annular contact member and a contact carried at and insulated from one end of the annular contact to coöperate with the contacts of a

- socket and arranged to engage the base and secure the members engaging in the openings in the base to the base.
2. In an electric attachment plug, a cylindrical block of insulating material externally screw threaded and having openings extending longitudinally therethrough, a threaded metallic sleeve adapted to be screwed onto the block, a metallic disk carried at the end of and insulated from the sleeve, and circuit terminal contact fingers to engage in the openings in the block and arranged to be firmly clamped to the block by the sleeve and end contact carried thereby and in electrical contact therewith as the sleeve is screwed onto the block.
3. In an electric attachment plug, a cylindrical block of insulating material externally threaded and having a pair of openings extending therethrough, a threaded metallic sleeve adapted to be screwed onto the block, a metallic disk carried at the end of and insulated from the sleeve, said disk having a central perforation, a circuit terminal contact finger to engage in one of the block openings and having a part to extend beyond the end of the block to engage in the disk opening when the sleeve is screwed onto the block to hold the same in electrical contact with said disk and clamp the finger to the block, and a circuit terminal contact finger to engage in the other block opening and having a part to lap over the wall of the opening to lie contiguous to the outer surface of the block to be engaged by the sleeve as it is screwed onto the block to hold the same in electrical contact with the sleeve and clamp the same to the block.
4. In an electric attachment plug, a block of insulating material externally threaded and having openings extending therethrough; a threaded metallic sleeve carrying a perforated disk at one end and insulated therefrom adapted to be screwed onto the block and to coöperate with the threaded shell contact and the disk with the end contact of a socket; a circuit contact terminal finger to engage in an opening in the block and having a part to project from the opening and engage in the disk perforation as the sleeve is screwed onto the block to clamp the finger to the block and hold the two in positive electrical contact; and a second circuit contact terminal finger to engage in the other opening in the block and having a part to lap over the side of the block to be engaged by the sleeve as it is screwed onto the block to hold the two in electrical contact and clamp the finger to the block.
5. In an electric attachment plug, a block of insulating material externally threaded and an opening extending longitudinally therethrough with a recess in the lateral wall of said opening; a circuit terminal contact finger arranged with a part to extend through the recess in the wall of the opening and lie contiguous to the outer wall of the block; and a threaded metallic sleeve adapted to be screwed onto the block to coöperate with the threaded shell of a socket and to engage in electrical contact with and clamp the contact finger to the block.
6. In an electric attachment plug, a block of insulating material externally threaded and having an opening extending longitudinally therethrough with a recess in one end of the block extending laterally from the opening; a circuit terminal contact finger to engage in the block opening, said finger having a part to engage over the shoulder formed by the recess in the end of the block and to extend beyond the end of the block; a threaded metallic shell; a perforated disk at one end of and insulated from the shell; said shell being adapted to be screwed onto the block, and as the sleeve is applied to the block the extended end of the finger adapted to engage in the disk perforation to thereby clamp the finger to the block and maintain the disk and finger in positive electrical contact.
7. An electric attachment plug, comprising a pair of members of insulating material, one member carrying binding terminals having contact fingers extending therefrom, and the other member having perforations therethrough for the reception of the terminal contact fingers of the other member; terminal contact fingers to engage in the perforations in the one member; means mounted on the perforated plug member including contacts to coöperate with the contacts of a socket and arranged to be maintained in contact with the terminal contact fingers and secure the fingers to said member.
8. An electric attachment plug, comprising a pair of members of insulating material; one member carrying binding terminals having contact fingers extending therefrom, and the other member having perforations therethrough for the reception of the terminal contact fingers of the other member; terminal contact fingers carried by the perforated member to engage in the perforations therein; a metallic sleeve mounted on the perforated member carrying a metallic disk at one end and insulated therefrom; said sleeve and disk being arranged to be held in contact with the latter fingers and secure the fingers to the insulating member, and said fingers being arranged to coöperate with the contact terminal fingers of the other member as they are inserted in the perforations therein to lock the two members of the plug together.
9. An electric attachment plug, comprising a pair of members of insulating material, one member carrying binding terminals having contact fingers extending there-

- 4
- from, and the other member having perforations for the reception of the contact terminal fingers of the other member; terminal contact fingers carried by the perforated member to engage in the perforations therein; means mounted on the perforated member constituting contacts to coöperate with the contacts of a socket and arranged to be held in contact with the fingers carried by the perforated member and secure said fingers to said member, and the portions of said fingers within the openings being arranged to clamp the fingers of the other member between the same and the wall of the perforations as they are inserted into the openings, and the fingers of both members having means to coöperate to releasably lock the members together.
10. An electric attachment plug, comprising a member of insulating material having openings therethrough; a threaded metallic sleeve to be screwed onto said member carrying a metallic disk at one end and insulated therefrom; contact terminal fingers mounted on said member with the ends to engage in the openings to be engaged by the sleeve and disk and held in contact therewith and secure the fingers to said member, and the ends of the fingers in the openings being provided with yielding portions; and a second plug member of insulating material carrying binding terminals with fingers extending therefrom adapted to engage in the openings of the other plug member to contact and coöperate with the yielding ends of the fingers therein to secure the plug members together.
11. An electric attachment plug, comprising a member of insulating material having openings therethrough; means mounted upon said member including an annular member and a disk member carried at and insulated from one end of the annular member to constitute contacts to coöperate with the contacts of a socket; fingers mounted upon the insulating member having a part to engage in the openings therein and with which fingers the contact means mounted upon the insulating member engage to secure the fingers to the insulating member; a second plug member of insulating material carrying binding terminals with fingers extending therefrom adapted to enter into the openings in the other plug member to contact with the ends of the fingers therein; and the fingers of both plug members being arranged to coöperate to lock the plug members together and which are adapted to be moved to locking position and released by the application of a predetermined force.
12. In an electric attachment plug, a member of insulating material having openings therethrough, a metallic sleeve to encircle said member carrying a metallic disk at the end and insulated therefrom, and contact terminal fingers to engage in the openings in said member; said fingers and sleeve being arranged whereby as the sleeve is applied to the insulator member the sleeve and said member will coöperate to clamp the fingers rigidly to the insulator member with one finger in electrical contact with the sleeve and the other finger in contact with the sleeve disk.
13. In an electric attachment plug, a member of insulating material having openings therethrough, a metallic sleeve to encircle said member carrying a metallic disk at the end and insulated therefrom, and contact terminal fingers to engage in the openings in said member, said fingers, member and sleeve being arranged whereby as the sleeve is applied to the insulator member the sleeve and said member will coöperate to clamp the fingers rigidly to the insulator member with one finger in electrical contact with the sleeve and the other finger in contact with the sleeve disk.

WILLIAM ILE.
